UNITED STATES PATENT OFFICE

168,548

MONOGRAMMED SPECTACLE FRONT

Samu-El Ish-Shalom, New York, N. Y.

Application May 24, 1952, Serial No. 19,874

Term of patent 14 years

(Cl. D57—1)

To all whom it may concern:

Be it known that I, Samu-El Ish-Shalom, a citizen of the United States of America, residing at New York, N. Y., have invented a new, original, and ornamental Design for a Monogrammed Spectacle Front, of which the following is a specification, reference being had to the accompanying drawings, forming a part thereof.

The essential features of my design reside in the ornamentation shown in full lines.

I claim:

The ornamental design for a monogrammed spectacle front, as shown and described.

SAMU-EL ISH-SHALOM.
